UNITED STATES PATENT OFFICE.

LESLIE H. FISHEL, OF NEW YORK, N. Y.

DESIGN FOR A JEWELRY ORNAMENT.

42,253.

Specification for Design.

Patented Mar. 5, 1912.

Application filed September 2, 1911. Serial No. 647,453. Term of patent 7 years.

To all whom it may concern:

Be it known that I, LESLIE H. FISHEL, a citizen of the United States, residing at the borough of Manhattan, city of New York, in the county of New York and State of New York, have invented a certain new, original, and ornamental Design for a Jewelry Ornament, of which the following is a specification, reference being had therein to the accompanying drawings, forming part thereof.

I claim:

The ornamental design for a jewelry ornament as shown.

LESLIE H. FISHEL.
